CLAIM

The ornamental design for a display screen with animated graphical user interface, as shown and described.

DESCRIPTION

FIG. 1 is the first image in a sequence of a front view of a display screen with an animated graphical user interface showing our new design;

FIG. 2 is the second image in the sequence thereof;

FIG. 3 is the third image in the sequence thereof;

FIG. 4 is the fourth image in the sequence thereof;

FIG. 5 is the fifth image in the sequence thereof; and,

FIG. 6 is the sixth image in the sequence thereof.

The outermost even-length broken lines illustrate an electronic device, which is the environment of the design, and form no part of the claimed design. The broken line showing of a display screen forms no part of the claimed design. The remaining even-length and dot-dash broken lines illustrate a user interacting with the electronic device, and form no part of the claimed design.
